[57] CLAIM

The ornamental design for an insect bait station, as shown and described.

DESCRIPTION

FIG. 1 is a perspective view of an embodiment of our new insect bait station;

FIG. 2 is a side view of the insect bait section shown in FIG. 1, all other sides being identical thereto;

FIG. 3 is a top plan view of the insect bait station shown in FIG. 1;

FIG. 4 is a bottom plan view of the insect bait station shown in FIG. 1;

FIG. 5 is a perspective view of an alternate embodiment of our new insect bait station;

FIG. 6 is a side view of the insect bait station shown in FIG. 5, all other sides being identical thereto;

FIG. 7 is a top plan view of the insect bait station shown in FIG. 5;

FIG. 8 is a bottom plan view of the insect bait station shown in FIG. 5.
